UNITED STATES PATENT OFFICE.

HENRY SPENGLER, OF NEW YORK, N. Y.

BOTTLE CAP.

Continuation of application Serial No. 462,515, filed April 19, 1921. This application filed February 19, 1924. Serial No. 693,849.

This application is a continuation of application Serial No. 462,515, filed Apr. 19, 1921.

The present invention is a closure for bottles and other containers, and the objects of the invention are to provide a cap of simple, inexpensive construction, capable of being easily applied and which can be removed without requiring any special tools.

10 In the accompanying drawing I have disclosed the invention embodied in some of its different forms, but wish it understood that further modifications may be made without departure from the true spirit of the invention, as will be apparent from the scope of the appended claims.

In the drawing referred to, Figure 1 is a top plan view of the cap;

20 Figure 2 is a side elevation showing the cap applied over the mouth of a bottle;

Figure 3 is a similar view, with the cap shown in section;

Figure 4 is a broken plan, and

Figures 5 and 6 are broken side views, 25 illustrating the construction and operation of the spring holding fingers;

Figures 7 and 8 are plan views, showing the blank as it is first punched and then as having certain of the fingers stretched and 30 spread to overlap the other spring fingers;

Figure 9 is a broken sectional view illustrative of a modification;

Figure 10 is a partial plan view, broken away, illustrating another modification; and

35 Figure 11 is an elevation of the subject-matter of Figure 10.

The cap shown is constructed of suitable spring material, usually spring sheet metal and is slitted at its periphery to provide the 40 two sets of holding fingers 10 and 11, the second mentioned set of fingers overlapping the edges of the first set of fingers, as indicated at 12 in Figure 1.

These spring holding fingers are turned 45 inwardly to provide hooks or claws 13 (Figure 3) to ride over and engage beneath a bead or shoulder 14 on the neck of the bottle 15 or other container to which the cover may be applied.

50 If desired, a suitable sealing gasket or washer 16 may be used in connection with the cap to make a liquid and gas-tight seal.

The cap is usually formed with a relatively high crown, as I have indicated at 55 17, the bases of the spring fingers merging

gradually into this crown as illustrated, which forms in effect a truss for bracing the fingers. This fact, in connection with the overlapping engagement of the fingers 11 over the inner set of fingers 10, provides a 60 holding engagement with the container which is sufficient for all practical purposes and one which at the same time will permit of the cap being readily detached from the container.

65 On this latter point it will be noted that the overlapping of the outer set of fingers causes these fingers to stand out so as to form in effect a projecting annular rim at 18 (Figure 3) forming a convenient finger-hold for "rocking" the cap free of the annular rib 14. This leverage may be accentuated by providing an outstanding fold or bead 18^a at the rim of the cap, substantially in line with the bend of the spring fingers, as I have 70 shown in Figure 9.

75 In making up the caps, blanks like that shown in Figure 7 may be used, said blanks being slitted radially on lines 19 to provide separate fingers, the alternate fingers or 80 wings thus produced being then swaged or otherwise treated as indicated at 20 in Figure 8 to stretch them and widen them out to an extent where they will overlie the edges of the intermediate wings. To make 85 the fingers more flexible the slits may be widened or opened out at the inner ends as by forming perforations 21 (Figures 7 and 8.)

80 Figure 5 indicates in a general way the relation of the overlapping fingers when the cap is seated in closed relation over the mouth of the bottle; whereas Figure 6 indicates how when the cap is being forced over the rib at the neck of the bottle, the 90 spring fingers will be forced open somewhat, this latter view showing how even in this latter relation the edges of the overlapping spring fingers will still overlie the edges of the underneath fingers.

95 The reinforcement of the inner spring gripping fingers by the overlying outer spring fingers provides a hold with the neck of the container which is both secure and will automatically compensate for slight 100 variations in the size of the rib and the fit of the cap.

105 This reinforcement of the spring fingers furthermore enables the cap being used repeatedly since the spring holding fingers do 110.

not become permanently distorted on removal from the bottle.

The annularly outstanding bulge or bead at the rim of the cap affords a convenient finger-hold beneath which the thumb may be engaged to force the edge of the cap upward and when once started in this way the spring of the fingers is ordinarily sufficient to "snap" the cap entirely free of the neck.

- 5 10 In order to eliminate the roughness of the surface of the cap, occasioned by the overlapping of fingers 11 with respect to fingers 10, I may raise parts of the surfaces of fingers 10, as for instance by providing corrugations 22 longitudinally of the fingers (radially of the cap), these corrugations standing out from the surfaces of fingers 10 so as to be flush with the surfaces of fingers 11 (Figure 10). Or raised spot-like areas 15 23 may be provided for the same purpose. With either construction the cap will present a comparatively smooth surface to the fingers of the operator.

Furthermore, the corrugations 22 or beads 25 23 will have the effect of strengthening the fingers, and this may be important where such a metal as aluminum is used in the making of the cap. For this purpose the beads or corrugations may be put on fingers 11 as 30 well as on fingers 10, and may either stand out from, or be depressed below, the outer surface thereof, preferably the latter, so that cap surface will be uniform.

What I claim is:

- 35 1. In a bottle closure, a cap provided with dependent, inturned spring fingers to ride over and engage beneath the bead of a bottle neck and yielding members integral with the cap and overstanding and reinforcing said 40 spring fingers.
2. In a bottle closure, a cap provided with dependent, inturned spring fingers to ride over and engage beneath the bead of a bottle neck and yielding members integral with the 45 cap and overstanding and reinforcing said

spring fingers, said yielding reinforcements being extended inwardly at points between the first mentioned spring fingers to constitute additional spring holding fingers.

3. In a bottle closure, a cap provided with 50 dependent, inturned spring fingers to ride over and engage beneath the bead of a bottle neck and yielding members integral with the cap and overstanding and reinforcing said spring fingers, said cap having an annular 55 outwardly bulged rim in the plane of the spring fingers to provide leverage for rocking the cap to disengage the spring fingers from holding engagement with the bead.

4. A closure for bottles and the like comprising a cap of spring material slitted at the edge to provide independent fingers, certain of said spring fingers being lapped over adjoining fingers to thereby reinforce the same.

5. A closure for bottles and the like comprising a cap of spring material slitted at the edge to provide independent fingers, certain of said spring fingers being lapped over adjoining fingers to thereby reinforce the same and both the overlapping and the underlapping fingers being extended inwardly to constitute spring jaws for gripping engagement beneath the bead of a bottle neck or the like.

6. A closure for bottles and the like comprising a cap of spring material slitted at the edge to provide independent fingers, certain of said spring fingers being lapped over adjoining fingers to thereby reinforce the same, said cap having a decided crown and 80 having an annular bead at the rim thereof to afford leverage for rocking the cap free of the neck of a bottle.

7. A closure as set forth in claim 5, in which the underlapping fingers are provided 85 with raised portions standing out flush with the surfaces of the overlapping fingers.

In testimony whereof I affix my signature.

HENRY SPENGLER.
